UNITED STATES PATENT OFFICE.

HENRY S. HUBBELL AND ALFRED S. HUBBELL, OF BUFFALO, NEW YORK.

DESIGN FOR A STOVE.

Specification forming part of Design No. 6,978, dated November 4, 1873; application filed October 10, 1873.
[Term of Patent 7 years.]

To all whom it may concern:

Be it known that we, HENRY S. HUBBELL and ALFRED S. HUBBELL, of the city of Buffalo, in the county of Erie and State of New York, have invented a Design for Stoves, of which the following is a specification:

The nature of our design is fully represented in the following photographic illustration to which reference is made.

Our invention relates to an oval or cylindrical heating-stove, having a cast-iron base and top plate with a body of sheet-iron.

Referring to the photographic illustration, A is the front plate of the stove, in which the two registers *a a* are arranged one above the other. The molding of this plate is ornamented with an outer row of diamond-shaped figures in relief, while the central portion around the registers has a roughened or pebbled background with scrolls in relief. B is the base-plate with three concentric rows or circles, *b b¹ b²*, of ornaments on the molding thereof. C is the main top plate with three concentric rows, *c c¹ c²*, of ornaments around the outer portion, while within these and surrounding the feed-hole is a band having a roughened background with a vine in relief. D is the swinging cover for the opening in the top plate, which is ornamented at the outer edge with a row of dental projections, *d*. Inside of this row is a band or circle of scroll ornaments in relief from a pebbled background. E is the

ornamental urn, which rests on the central portion of the cover D.

We claim—

1. The design herein shown for the front plate A, having the two registers *a a* arranged one above the other, the molding surrounding the same ornamented with a row of diamond-shaped figures, while the central portion around the register has a pebbled background with scrolls in relief.

2. The design herein shown for the base-plate B, consisting of three concentric rows or circles, *b b¹ b²*, of ornaments on the molding thereof.

3. The design herein shown, for the main plate C, of three rows, *c c¹ c²*, of ornaments around the outer portion, while within these and surrounding the feed-hole is a band having a roughened background with a vine in relief.

4. The design herein shown for the swinging cover D, consisting of the outer row of dental projections *d*, inside of which is a band or circle of scroll ornaments in relief from a pebbled background.

5. The design herein shown for the urn E, consisting of the "ogee" base and ornamental handles.

HENRY S. HUBBELL.
